United States Patent Office

Des. 201,452
Patented June 22, 1965

201,452

CLOCK

Robert C. Shipley, Kalamazoo, Mich., assignor to R. C.
Shipley Mfg. Co., Portage, Mich., a corporation of
Michigan

Filed Jan. 2, 1964, Ser. No. 77,995

Term of patent 14 years

(Cl. D42—7)

FIGURE 1 is a front perspective view of a clock showing my new design;

FIGURE 2 is a rear perspective view thereof;

FIGURE 3 is a right side elevational view thereof;

FIGURE 4 is a left side elevational view thereof;

FIGURE 5 is a top view thereof taken at right angles to the clock face; and

FIGURE 6 is a rear view of FIGURE 5.

The dominant features of the design reside in the portions shown in full lines.

I claim:

The ornamental design for a clock, as shown and described.
